UNITED STATES PATENT OFFICE.

THOMAS A. HOOVER, OF FRESNO, CALIFORNIA, ASSIGNOR TO AMERICAN CHAIN COMPANY, INC., A CORPORATION OF NEW YORK.

CLAMP FOR ATTACHING BUFFERS TO VEHICLES.

1,397,213.

Specification of Letters Patent.

Patented Nov. 15, 1921.

Application filed September 22, 1921. Serial No. 502,409.

To all whom it may concern:

Be it known that I, THOMAS A. HOOVER, a citizen of the United States, residing at Fresno, in the county of Fresno, State of California, have invented certain new and useful Improvements in Clamps for Attaching Buffers to Vehicles, of which the following, taken in connection with the accompanying drawings, is a specification.

10 My invention relates to clamps or attaching devices for attaching buffers to the frames of automobiles.

One object of the invention is to provide an automobile buffer attaching clamp of such character as to dispense with the necessity of punching or giving special form to the supporting arms of the buffer which is to be attached to the automobile by means of the clamp.

20 Another object is to provide a clamp of the above described character that will permit the supporting arms, and consequently the buffer bar, to be raised and lowered to various horizontal positions.

25 Another object is to provide a bumper of the same character as the first above described adapted to permit the supporting arms to be moved forwardly and rearwardly with respect to the car when the clamping means are loosened and firmly retained in any desired position within their range of movement when the clamping means are tightened.

Another object is to provide a clamp of the character above described adapted for attachment to a channel bar by engagement with one flange only.

Referring to the drawings:

Figure 1 is a plan view of the front portion of an automobile of conventional type showing a bumper attached thereto by the clamp which is the subject matter of this invention.

Fig. 2 is a view in elevation of the inner side of an automobile frame showing the clamp engaged therewith and also retaining a supporting arm of a buffer.

Fig. 3 is a view on the lines 3—3 of Fig. 2.

Fig. 4 is an enlarged detail plan view 50 of the forwardly projecting end of the longitudinal bars of an automobile frame showing the clamp engagement therewith and

also retaining a buffer arm, the parts being broken away to more clearly show the details of construction.

Fig. 5 is a view in elevation of the inner side of the bearing member.

Fig. 6 is a view in elevation of the grooved or inner side of the clamping plate.

Fig. 7 is a view in elevation of the grooved or inner side of a modified form of clamping plate.

Fig. 8 is an end view of the clamping plate shown in Fig. 7.

In the drawings I have shown my clamp in use in connection with an automobile frame of a conventional type, having as a part of its structure two longitudinally disposed channel bars made up of the upper flanges 1, the lower flanges 2, the webs 3. The supporting arms 4 sustain the bumper bar 5 which is likewise shown as of conventional type being composed of flat strip steel adapted for vertical rigidity but for horizontal resiliency.

The nature of the device requires that a pair of the clamps be used on each vehicle, but as they are preferably duplicates of one another a description of one only is given.

Any suitable means may be used for engagement with the channel bar. By preference I make use of a form of construction which can be attached to frames of those types of cars which are provided with mud guards and splash pans connected to the channel bars in such manner as to make difficult the utilization of the upper flange. A suitable construction for this purpose may consist of a hook comprising the shank 6 and the tip 6^a, the mouth of the hook being properly proportioned to firmly embrace the lower flange 2 of the channel bar. To make possible a rigid engagement of the hook and of the entire clamp with the channel bar, I also provide a bearing plate comprising the vertical portion 7 and the horizontal portion 8 the latter projecting from the vertical portion at substantially right angles in such manner that the bearing plate as a whole closely fits the angle of the channel bar formed by the web and the flange.

The bearing plate is provided with an aperture 9 so positioned that when the hook is in engagement with the channel bar and

the bearing plate is positioned in close contact with the channel bar, the shank of the hook passes through the aperture and projects for a substantial distance beyond the 5 outer side of the vertical portion 7. As the webs of the forward ends of the channel bars of most motor cars have rivet heads which would prevent close contact of a perfectly flat plate with the webs, I find it advisable 10 to provide the inner face of the vertical portion 7 of the bearing plate (see Fig. 5) with depressions or cavities 10 adapted to fit over rivet heads as they are ordinarily disposed.

For securing the arm of a buffer firmly 15 against the bearing plate, I provide a clamping plate 11 having the groove 12 shown in this instance as of rectangular cross-section and adapted to slidably fit the buffer arm 13. This plate also is provided with an aperture 14 adapted to register with the aperture 9 so that the shank of the bolt may project not only through the bearing plate but also through the clamping plate when the latter is brought up against the bearing plate.

25 It is thus obvious that the clamping plate is adapted to pivot on the shank of the bolt while the bearing plate remains fixed and that a considerable range of adjustment may be effected by swinging it one way or the 30 other on its pivotal connection with the bolt shank.

In order to retain the clamping plate in any desired position within the range of movement which would ordinarily be required under service conditions, I provide the vertical portion of the bearing plate with a slot 15 preferably struck on an arc having the aperture 9 as a center. The clamping plate is also provided with a slot 16 in a 40 similar manner preferably struck on an arc having the aperture 14 as a center and adapted to register with the slot 15. Through the registering slots 15 and 16 the clamping bolt 17 provided with the clamping nut 18 may 45 be passed. Under many conditions the head 19 of the clamping plate might interfere with mud guards and splash pans or other attachments, and therefore it is advisable to countersink the vertical portion of the bearing plate as shown at 20 so that the head 19 of the clamping bolt will at all times be flush with the inner face of the vertical portion of the bearing plate. The shank 6 of the supporting bolt is provided with a nut 50 21 which, as will be obvious, serves to clamp all of the parts firmly together and to retain the clamp in firm engagement with the channel bar.

It is preferable that the bearing plate and 60 the clamping plate both be of substantial length for the reason that friction is the only means for preventing the supporting arm 13 from being driven through the groove 12 under the action of a force such as the shock 65 of a collision.

It will be obvious that by merely loosening the nut 18 and also by preference the nut 21, the supporting arm of the buffer may be raised or lowered to any desired position within the range of movement permitted by 70 the slots 15 and 16.

An arrangement such as shown in Figs. 7 and 8 may be used if desired. In Fig. 7 the slot for adjustment is indicated by the numeral 23, being at the lower edge of the 75 clamping plate and the aperture whereby the clamping plate is adapted for pivotal motion is found at the top and indicated by the numeral 22. In the case of this modification, the shank of the bolt 17 acts as a pivot while 80 the adjustment is made by swinging the clamping plate on this pivot and clamping it by means of the nut 21. The last described arrangement is merely the reverse of the arrangement shown in Figs. 1 to 6.

Having thus described my invention and with the knowledge that changes and modifications may be made that are within the ability of the ordinary skilled mechanic but which nevertheless do not depart from the 90 spirit thereof, I claim:

1. In a clamp for attaching a buffer to the channel bars of an automobile, a pair of contacting plates pivotally connected to each other to adapt them for relative oscillation 95 in adjacent planes, the contacting surfaces of one of said plates being provided with a groove displaced from the point of pivotal connection, said groove serving to receive a buffer supporting arm, means for clamping said plates together in a plurality of angular positions with respect to each other and with respect to said point of pivotal connection and means for attaching one of said plates to a channel bar.

2. In a clamp for attaching a buffer to the channel bars of an automobile, a pair of contacting plates of substantial length pivotally connected to each other to adapt them for relative oscillation in adjacent planes 110 the contacting surface of one of said plates being provided with a groove displaced from the point of pivotal connection said groove serving to receive a supporting arm of the buffer, means for clamping said plates together in a plurality of angular positions with respect to one another and means for attaching one of said plates to a channel bar.

3. In a clamp for attaching a buffer to the channel bars of an automobile, a pair of contacting plates pivotally connected to each other to adapt them for relative oscillation in adjacent planes, the contacting surface of one of said plates being provided 125 with a groove displaced from the point of pivotal connection, said groove serving to receive the supporting arm of a buffer, registering slots in said plates and a clamping bolt connecting the said plates by means 130

- 65 of said slots and means for attaching one of said plates to a channel bar.
14. In a clamp for attaching a buffer to the channel bars of an automobile, a pair of contacting plates pivotally connected to each other to adapt them for relative oscillation in adjacent planes, the contacting surface of one of said plates being provided with a groove displaced from the point of pivotal connection, said groove serving to receive the supporting arm of a buffer, registering slots in said plates and a clamping bolt connecting the said plates by means of said slots said pivotal connection being established by the shank of a hook bolt said hook bolt being adapted to support the said clamp by engagement with a flange of the channel bar.
15. In a clamp for attaching a buffer to the channel bars of an automobile, a pair of contacting plates pivotally connected to each other to adapt them for relative oscillation in adjacent planes, the contacting surface of one of said plates being provided with a groove displaced from the point of pivotal connection said groove being adapted to receive the supporting arm of a buffer, means for clamping said plates together in a plurality of angular positions with respect to each other, a hook bolt adapted to engage a flange of said channel bar said hook bolt having a shank extending through said plates and constituting the means of pivotal connection and means for drawing said plates and the shank of said hook bolt into close contact with the web of a channel bar.
6. In a clamp for attaching a buffer to the channel bars of an automobile, a pair of contacting plates pivotally connected to each other to adapt them for relative oscillation in adjacent planes, the contacting surface of one of said plates being provided with a groove displaced from the point of pivotal connection to receive a supporting arm of the buffer, registering slots in said plates concentric with the said point of pivotal connection, a clamp bolt extending through said slots and adapted for drawing the plates together into clamping relation and a bolt passing through apertures in said plates and establishing said pivotal connection said bolt having a hooked end adapted to firmly engage one of the flanges of said channel bar and means for drawing the said bolt and the said plates together into clamping relation with the channel bar.
7. In a clamp for attaching a buffer to the channel bar of an automobile, a pair of contacting plates pivotally connected to each other to adapt them for relative oscillation in adjacent planes, the contacting surface of one of said plates being provided with a groove displaced from the point of pivotal connection for receiving the supporting arm of a buffer and the other of said plates having an extension adapted to extend along the outer side of a flange of a channel bar, means for clamping said plates together in a plurality of angular positions with respect to each other and means for attaching one of said plates to the said channel bar.
8. In a clamp for attaching a buffer to a channel bar of an automobile, a pair of contacting plates pivotally connected to each other to adapt them for relative oscillation in adjacent planes the contacting surface of one of said plates being provided with a groove displaced from the point of pivotal connection for receiving the supporting arm of a buffer, registering apertures in said plates, one of said apertures consisting of a slot, a clamping bolt extending through said aperture and adapted to clamp the said plates together in a plurality of angular positions with respect to one another and means for attaching one of said plates to the said channel bar.
9. In a clamp for attaching a buffer to a channel bar of an automobile, a pair of contacting plates pivotally connected to each other to adapt them for relative oscillation in adjacent planes the contacting surface of one of said plates being provided with a groove displaced from the point of pivotal connection for receiving the supporting arm of a buffer, registering apertures in said plates, one of said apertures consisting of a slot, a clamping bolt extending through said aperture and adapted to clamp the said plates together in a plurality of angular positions with respect to one another and means for attaching said plates to the said channel bar the said means consisting of a hook bolt having a shank passing through and constituting the said pivotal connection.
10. In a clamp for attaching a buffer to a channel bar of an automobile, a pair of contacting plates pivotally connected to each other to adapt them for relative oscillation in adjacent planes the contacting surface of one of said plates being provided with a groove displaced from the point of pivotal connection for receiving the supporting arm of a buffer, registering apertures in said plates, one of said apertures consisting of a slot, a clamping bolt extending through said aperture and adapted to clamp the said plates together in a plurality of angular positions with respect to one another and means for attaching said plates to the said channel bar the said means consisting of a hook bolt having a shank passing through and constituting the said pivotal connection.
11. In a clamp for attaching a buffer to the channel bars of an automobile, a bearing plate having a portion adapted to be posi-

- tioned against the outer side of the web of said channel bar, a clamping plate pivotally connected with relation to said portion and adapted to be oscillated in a plane adjacent the plane of said portion, said clamping plate being provided with a groove adapted to receive a supporting arm of a buffer and means for clamping said clamping plate against said portion.
- 10 12. In a clamp for attaching a buffer to the channel bars of an automobile, a bearing plate having a portion adapted to be positioned against the outer side of the web of said channel bar, a clamping plate pivotally mounted with relation to said portion and adapted to be oscillated in a plane adjacent the plane of said portion, said clamping plate being provided with a groove adapted to receive a supporting arm of a buffer, and means for clamping said clamping plate against said portion in a plurality
- 5 of angular positions with respect to the point of pivotal mounting.
13. In a clamp for attaching a buffer to the channel bars of an automobile, a bearing plate having a portion adapted to be positioned against the outer side of the web of said channel bar and another portion adapted to lie against one of the flanges of said channel bar, a hook bolt adapted to 25 embrace the said flange and having a shank adapted to extend through an aperture in said bearing plate a clamping plate pivotally mounted on said shank and having a groove adapted to receive the supporting 30 arm of a buffer bar, said bearing plate and said clamping plate being provided with registering slots, and a bolt connecting said plates by means of said slots.
- 15 In testimony whereof, I have signed this 40 specification.

THOMAS A. HOOVER.
